Company, Rochester, N. Y., a corporation of
New Jersey

Application October 13, 1937, Serial No. 168,778

1 Claim. (Cl. 179—100.3)

This invention relates to sound recording and particularly to variable area push-pull recording.

It is an object of the invention to provide a variable width track suitable for push-pull reproduction of the class B type. As is well known, a class B push-pull record carries only the positive half of each cycle in one side of the track and the negative half only in the other side of the track.

In the preferred embodiment of the invention only a single track is recorded which can be used, however, for push-pull reproduction. Incidentally, by masking a narrow central portion of the track, it may be made to appear as two separate tracks, but is actually just a single track or at least a track recorded from a single beam of light.

It is the primary object of the invention to provide a simple ribbon valve circuit capable of providing such a track.

According to the invention a ribbon valve is provided having two parallel ribbons in a strong magnetic field, each ribbon arranged parallel and under tension in the usual manner. The two ribbons, according to the invention, are insulated from each other and each is separately connected through a half-wave rectifier across an input circuit carrying the signal to be recorded or a portion thereof. The advantages of half-wave rectifiers in this connection are disclosed in a copending application filed concurrently herewith Serial Number 168,777, now Patent No. 2,161,369, to McLeod (one of the present inventors) and Morse. The present arrangement accomplishes somewhat the same result as therein disclosed, but in a much simplified manner. It is, however, confined to variable area recordings.

The rectifiers are arranged to permit current to flow only in the direction (determined with respect to the magnetic field) which causes each ribbon to move in a lateral direction away from the other ribbon. Thus the two rectifiers must be oppositely connected.

The invention will be more clearly understood from the following description when read in connection with the accompanying drawing in which:

Fig. 1 shows a sound recording system incorporating the invention.

Fig. 2 shows a portion of a positive sound track made according to the invention.

Fig. 3 illustrates how such a track can be produced using a galvanometer type valve.

In Fig. 1 the signal picked up by a microphone 10 is passed through an amplifying system 11 to the input 12 of a transformer having a secondary

13 connected to supply current to two single ribbon light valves 16 and 17. These ribbons actually are mounted in a single light valve but are electrically insulated from each other except for the external circuit as shown. A half-wave rectifier 18 in series with the ribbon 16 permits only one half (e. g., positive half) of the input signal to pass through this ribbon 16. The magnetic field of the valve is such that this current causes the ribbon 16 to move away from the ribbon 17. A rectifier 19 in series with the ribbon 17 similarly permits it to move only in a direction away from the ribbon 16.

Each of the ribbons may have a separate secondary or may be connected across only a portion of the secondary 13. The simple arrangement shown appears to be preferable, however.

An optical system comprising a lamp 20, lenses 21 and 21', slit diaphragms 22, and a cylindrical lens 23, projects an image of the space between the two ribbons to a sensitive film 24 falling on the portion 25 intended for the sound record. The usual picture area is indicated as 26.

When there is no input signal the points 14 and 15 at the end of the secondary 13 are at the same potential and hence both ribbons remain stationary and are adjusted to be very close together. The image of the space between the ribbons as focused by the lenses 21' and 23 on the film 24 then appears as a narrow band having a width S₀. On one half of each cycle of any input signal the point 14 is positive with respect to the point 15 and hence a current flows through the valve ribbon 17 and rectifier 19, but is prevented from flowing through the valve ribbon 16 by the rectifier 18. The usual magnetic field is oriented so that this current causes the ribbon 17 to move away from the ribbon 16 which remains in its zero position throughout this half of the input cycle. The appearance of the recorded sound track is indicated on the drawing.

It will be noted that the sound record either in the negative or in the positive appears as a single track running lengthwise of the film, more or less centrally located on the area provided therefor and having a width which remains constant when no signal is being recorded, but whose edges vary in accordance with a half wave rectification of the sound wave, in an outward direction only and alternately so that when one edge 50 is varying the other edge remains constant.

Although the present invention is not primarily concerned with galvanometer type recording valves, Fig. 3 is included to show how a track similar to that shown in Fig. 2 could be made 55

with a galvanometer system. A lamp 30 projects light through a lens 31, a mask 32 having a distorted hour-glass shaped aperture 33 and through a lens 34 to the mirror 35 of a galvanometer. An image of the mask 32 is projected on a slit 37 in a mask 36. This image 38 moves up and down when the mirror 35 vibrates in accordance with the sound modulations. The width of the band 39 of light formed by this image 38 and the slit 37 is focused by an optical system 40 on a film, not shown, to form a track having a form similar to that shown in Figs. 1 and 2.

Considering again the invention as shown in Fig. 1, it will be noted that a mask placed between the ribbons or at any real image of this area such as at the film 24 will cause the central band S₀ to appear light in the negative and dark in the positive. Such an arrangement would tend to decrease the transmission of the positive track for low volume signal and hence would be per-

haps even more "noiseless" than the arrangement shown. However, the advantages gained in this direction would be small since class B recordings are, of course, noiseless to a considerable degree. The arrangement shown is, therefore, preferable because of its simplicity. 5

What we claim and wish to secure by Letters Patent of the United States is:

An electric circuit for noiseless push-pull sound recording comprising an input circuit, a light valve having two single ribbons in a magnetic field, means connecting each ribbon across a portion of the input circuit and a half-wave rectifier in series with each ribbon, said rectifier for one ribbon having a direction of action opposite to that of the other rectifier and such with respect to the magnetic field that a current passing therethrough causes the ribbon to move laterally away from the other ribbon. 10
